APPARATUS FOR OPENING AND CLEANING
FLAX STRAW AND SUCH LIKE FIBROUS
MATERIALS

Henry Wilkinson and Norman Pilkington, Oldham, England, assignors of one-third to Platt Brothers and Company Limited, Oldham, England

Application November 17, 1936, Serial No. 111,256
In Great Britain November 25, 1935

7 Claims. (Cl. 19—90)

This invention has to do with an apparatus for opening and cleaning flax straw, bast fibres and such like fibrous materials, that is, an apparatus for cleaning and opening the more fibrous constituent and for getting rid of the non-useful wood and skin or unwanted detached particles commonly styled "shive".

The invention concerns an apparatus to which the flax straw or the like (if necessary previously treated) can be fed or delivered mechanically or otherwise, and which has some features in common with the well-known "Crighton" or vertical opener used in the cotton trade.

The proposed apparatus differs from a "Crighton" opener in a number of respects, as for example, in that the beater and surrounding grids or cage are not located in a closed outer casing, but in a casing which can breathe in order to allow the "shive" (which is comparatively light, as contrasted with the weight of impurities and trash carried in cotton) to be carried through the open work cage and deposited in the casing capable of breathing by the action of a generated air current. In order to assist in opening and cleaning the flax straw, and to generate the air current, a revolving propeller or impeller is located at or near the bottom of the beater, and such impeller operates in a fluted dish or annular trough which has internal ribs, corrugations, bars, or such like, with any approved disposition advantageous to the purpose, and hereafter called a roughened trough, and with which the vanes, blades, or equivalent parts of the impeller co-operate.

There is provision to admit air to the roughened trough for the impeller to generate the air current and also to permit the flax straw mass or the like to be delivered thereto.

The surrounding grids or cage to the revolving beater are not like the "Crighton" grids, but are so fashioned or of a character to suit the service, and different kinds of simple reticulated grids may be used, the same constituting an open-work cage surrounding the revolving beater, the upper rotating elements of the latter drawing in air and acting partly as a fan to discharge the opened material from the top of the cage.

The outer casing surrounds the cage, the beater and the impeller, and is of such size or dimensions as to produce an ample compartment to receive the trash and such casing is not air tight or closed but has pervious areas. From the top of the apparatus there may be an air trunk or tube or receiving outlet which can be coupled to a cage structure or any equivalent receiving,

delivery or conveying apparatus, and which may combine one or more pervious cage contrivances in a housing with stripping, damping or other provision, and by which the cleaned, opened and collected fibrous material can be delivered into any receptacle or other apparatus or to means to carry or otherwise transport the delivered fibre to the place desired. Similar or suitable means may be provided for feeding the fibrous material to the apparatus.

The apparatus making use of the features generally enumerated above is especially distinguished in this, that there is an enveloping pervious casing capable of breathing and an impeller located in a roughened trough below a revolving beater with an open-work cage, said impeller drawing the flax straw into the trough device and generating a powerful air current and assisting to open the flax straw and loosen the "shive" which "shive" is thrown out into the pervious casing by the generated air current passing outwards through the lower part of the open-work cage whilst the revolving beater acts on and lifts the opened fibrous material, the upper revolving elements of said revolving beater also drawing air inwards from the enclosing pervious casing into the upper part of the open-work cage which air induces and assists to carry the open fibre from the top of the open-work cage into the conveying tube or outlet ready to be removed.

An apparatus for the purposes described and embodying the foregoing features will now be described and explained with reference to the accompanying drawings, wherein:

Fig. 1 shows a sectional elevation of the cleaning and opening apparatus for the fibrous material stated.

Fig. 2 is an outside elevation.

Fig. 2a shows a detail sectional view of one of the pervious panels.

Fig. 3 is an outside elevation of the apparatus showing a suitable mechanical feed and mechanical delivery arrangement combined therewith.

Fig. 4 is a sectional plan view on the line 4—4, Fig. 1, showing the roughened trough and impeller.

Fig. 5 shows a separate and enlarged view of the impeller.

Fig. 5a is a side view of the impeller.

Fig. 6 is a sectional plan on the line 6—6, Fig. 1.

Fig. 7 is a separate broken view of the roughened trough, and,

Fig. 8 is a broken sectional view of the roughened trough.

structures constituting the surrounding wall of the open-work cage.

Fig. 9a is a detail section of inclined bars of the grid shown in Fig. 9 and elsewhere.

5 Fig. 10 is an enlarged and broken view of the driven upright shaft, the beater and the striker arms.

10 There is used a housing compartment or casing *a*. This has movable or removable walls or panels *a*¹, the panels being of a pervious nature, as for example canvas or openwork fabric panels can be used mounted in frame-work supports, the frame-work supports being secured by hinged catches *a*². There is a fluted dish or annular 15 trough hereafter referred to as a roughened trough *b* and this is shown as having ribs marked *b*¹, see Figs. 1, 4, 7 and 8, such roughened trough *b* having an inlet or feed slot *b*². This roughened trough *b* is stationary and is supported a 20 short distance from the floor of the casing *a* and air can obtain admission to the interior thereof through the open base. Within the roughened trough *b* is disposed an impeller (shown as consisting of inclined blades *c* fixed to inclined ribs 25 *c*¹ cast on the boss *c*²), the same being fixed to a rotatable shaft *c*¹ the lower end of which is supported in a step bearing *c*². This rotatable shaft *c*¹ can be driven through a pulley *c*³ and also supports a revolvable beater *d* preferably 30 of an inverted conical type the spaced discs of which are shown as carrying strikers *d*¹ variously inclined or arranged. The vertical shaft *c*¹ is driven at a high speed so that the impeller *c* and revolvable beater *d* are rotated at a high 35 speed. The impeller *c* draws the flax straw or the like, and also air along the feed pipe *e*, via the feed slot *b*² into the roughened trough *b*, the impeller opening the flax straw by the action of the blades against the flutes or ribs *b*¹ of the 40 roughened trough *b*, throwing the opened fibre and the "shive" upwards into the surrounding open-work cage *g* where the beater *d* operates.

The fibre is there further acted upon the bulk of the air induced by the impeller is discharged 45 outwards through the grids in the lower part of the open-work cage *g* which surrounds the beater *d*, the air discharged therethrough carrying the "shive" (unwanted material) along with it so that same can be deposited in the casing *a*. 50 The cleaning and separation is effected by centrifugal and beating action in the presence of a plentiful supply of circulating air. The comparatively light waste is thrown out and deposited in the casing *a*, as, due to the pervious panels 55 *a*¹, air can readily circulate and pass through the surrounding open-work cage structure marked as a whole *g* outwards and inwards, because the surrounding casing *a* is not sealed or closed as is a "Crighton" opener. Therefore air is freely 60 circulated through the surrounding open-work cage *g*, because the casing *a* can breathe and so the opening apparatus can function effectively to permit the throwing out and deposit of the "shive" within the casing *a* with pervious panels 65 *a*¹.

The revolving beater *d* is so constructed and provided with strikers and the whole arrangement is such that it has a tendency to ensure an effective opening as also a fan or lifting action, and 70 its upper revolving elements by exercising a fan-like action draw air through the upper part of the open-work cage *g* which air assists the forwarding of the cleaned and opened material to the outlet as at *f*.

75 The grid structure of the cage *g* may consist

of spaced frames *g*¹, *g*² each having an upright and an inclined side. The upper horizontal edges may hook under a rim or projection *a*⁴ whilst the lower horizontal edges fit on a ledge *b*³ of the roughened trough *b* and are embraced by an encircling band *b*⁴ see Figs. 1 and 9. In the one set of frames *g*¹, spaced steel bars of narrow blade-like cross-section *g*³ may be mounted and these are inclined to the vertical producing upright gaps whilst the other alternate frames *g*² 10 may be fitted with woven wire grids *g*⁴ presenting rectangular or other apertures, the drawings showing square apertures. Through these gaps and apertures the "shive" is carried by the circulating air current generated by the impeller *c* 15 and assisted by the beater *d* and this "shive" settles in the casing *a* and can be emptied out for example by opening the pervious frames or doors *a*¹.

The Fig. 3 illustrates, by way of example only, 20 an approved feed and delivery arrangement for use with the opening apparatus described. In this, the fibrous material to be treated is fed to trunk or pipe *1* and passes to a revolving cage or condenser *2* to the interior of which a fan *3* is 25 coupled.

The material is removed from the cage *2* by 30 a revolving ribbed stripper *4* and passes along the pipe *e* to the slot *b*¹ in the roughened trough *b*. The delivery arrangement is similar, the opened fibrous material passing along the trunk or pipe *5* to a cage or condenser *6* with coupled fan *7*, a ribbed stripper *8* discharging the open fibrous material. The means for feeding the fibrous material to the cleaning and opening apparatus and for delivering same can be greatly varied.

The encircling screens of the open-work cage *g* for the revolving beater *d* are in any case of such a construction that they tend to resist the passing through of valuable opened fibre, and the grid sections are capable of being readily detached or changed to suit a change in size or shape of gap or aperture in the grid elements appropriate to the particular class of material, 40 but the character and arrangement of grid structure shown is appropriate for dealing with flax straw.

We claim:

1. Apparatus for the purposes stated, comprising a casing, pervious panels to said casing permitting said casing to breathe, a compartment in said casing for deposit of "shive", a roughened trough in said casing, means to conduct the fibrous material to said trough, an inlet to said trough for fibrous material and air, an impeller in said trough, a conical cage above said trough comprising frames with panels of inclined bars, and frames with panels of woven wire, a revolving conical beater operating in said conical cage, said beater having strikers and operating to assist discharge of the opened material, and an outlet for said opened material.

2. Apparatus for cleaning and opening flax straw, bast fibres and such like, comprising a pervious casing, means to supply the fibrous material, a trough in said casing, an impeller structure rotatable in said trough thereby to set up a centrifugal action to throw out shive, an inlet to said trough for fibrous material, an open-work cage above said trough, an independent revolving beater superposed above the impeller and operating in the open-work cage and exercising an inward breathing action, an outlet into which the opened material is projected by said inward

breathing action, and a deposit chamber enclosed by the pervious casing.

3. Apparatus for cleaning and opening flax straw or such like, comprising a pervious casing, a roughened trough at the base of said casing, an impeller element in the trough to draw in and act on the flax straw or the like, an open-work cage above said trough, an independent revolving beater superposed above the impeller, said impeller operating to discharge air outwards through the lower part of said open-work cage to carry out the "hive", said independent revolving beater inducing air into the upper part of the open-work cage and an outlet from the cage into which the air induced by said beater carries the opened material.

4. Apparatus for the purposes stated comprising a pervious casing, a trough in said casing, an inlet to the trough, an impeller working in the trough, an open-work cage above the trough, an independent revolving beater disposed above the impeller, strikers on said beater, the impeller discharging air by centrifugal action to carry the shive through the lower part of the open-work cage, and the revolving beater inducing air inwardly into the upper part of the open-work cage, said inwardly induced air acting to remove the cleaned and opened material.

5. Apparatus for the purposes stated including a casing, a shive receiving compartment in the casing, pervious panels therefor, a roughened trough in the base of the casing, a feed inlet for the fibrous material, an impeller rotatable in said trough and operating to induce the fibrous material, an open-work cage above said trough, an independent revolving beater operating in said open-work cage, a series of strikers

on said beater, an outlet from the open-work cage, said independent revolving beater inducing a current of air through the upper part of the open-work cage to carry the cleaned and opened material to an outlet.

6. Apparatus for the purposes stated comprising a pervious casing, a roughened trough in the base of said casing, means to convey fibrous material to the trough, an impeller working in said trough, a conical cage above said trough, comprising removable open-work frames, an independent revolvable conical beater operating in said conical cage, strikers on said beater, said impeller discharging the shive outwardly into the pervious casing, and the revolving conical beater inducing air into the upper part of the conical cage to discharge the opened material to an outlet and combined means for delivering the opened material.

7. Apparatus for the purposes stated, comprising a casing, pervious panels to said casing, means to removably fix said panels, mechanical means to feed material to the apparatus, a roughened trough at the base of said casing, an inlet to the trough, an impeller working in said trough, a conical cage located above said roughened trough, open-work panels constituting the annular wall of said cage, an independent revolving conical beater in said cage, strikers on said beater, said impeller discharging the shive outwardly through the lower part of the cage, and said beater inducing air inwardly through the cage to convey the opened material out of the apparatus, and means to deliver the opened material.

HENRY WILKINSON.
NORMAN PILKINGTON.
